UNITED STATES PATENT OFFICE.

MARGARET WILLIAMS, OF BIRMINGHAM, ALABAMA.

LOCKING DEVICE.

No. 909,726.

Specification of Letters Patent.

Patented Jan. 12, 1909.

Application filed October 26, 1907. Serial No. 399,244.

To all whom it may concern:

Be it known that I, MARGARET WILLIAMS, a citizen of the United States, residing at Birmingham, in the county of Jefferson and State of Alabama, have invented new and useful Improvements in Locking Devices, of which the following is a specification.

This invention relates to improvements in soap holders, and the object of the invention is to provide a receptacle for soap consisting of perforated pliable material adapted to be suspended in proximity to a wash basin and provided with means for preventing the soap from being removed from its casing and suspension by unauthorized persons.

To these and other ends, the invention consists in the novel construction of soap holders hereinafter fully described and claimed.

In the drawings, Figure 1 is a perspective view of the invention illustrating the improved holder containing a cake of soap and being in a suspended position. Fig. 2 is a detail perspective view of the pliable holder showing the parts in an open position.

As illustrated in the drawings my improved soap holder comprises a substantially bag shaped structure composed of a perforated receptacle of rubber or other suitable pliable material having the front face 1 and the rear face 2.

The front face 1 is provided near its upper extremity with an eye 3 and a staple 4 while the rear face is provided with a closing flap 5 provided with the openings 6 and 7, which when the flap is closed are adapted to engage with the eye 3 and the staple 4 upon the front face of the holder.

40 A suitable strap 8 is also provided upon the rear face 2 of the holder and when the receptacle is closed, as shown in Fig. 1 of the drawing, the strap is adapted to pass under

the eye 3 and is provided with the opening 9 for engagement with the staple 4. 45

A suitable handle is provided upon the receptacle, as at 10 whereby a holder may be suspended from a hook 11 or any other desired suspending means.

50 A limiting chain 12 provided with an enlarged ring 13 is inserted through the staple 4 when the parts are in closed position, shown in Fig. 1 of the drawing, and the receptacle thus securely locked.

From the above description it will be 55 readily seen that the soap within the holder is adapted to be used without its removal from the receptacle. The perforations within the pliable casing of the holder, allowing for the free use of the soap and the limiting 60 chain 12, effectively prevents its removal by unauthorized persons.

The front face 1 of the holder has formed thereon teeth or nipples 14, as clearly shown in the figures of the drawing. With this 65 construction it will be noted that I have effectively produced a combined brush and soap holder which is adapted to be hung within the easy reach of the user and the construction of which is extremely simple, 70 cheap and durable.

Having thus fully described the invention what is claimed as new is:

A soap holder comprising a bag constructed of pliable material having its front and 75 rear sides each formed of two series of parallel strips intersecting each other, and its front face provided with rows of teeth projecting outwardly from both series of the strips on that side of the bag. 80

In testimony whereof I affix my signature in presence of two witnesses.

MARGARET WILLIAMS.
